(57) **CLAIM**

The ornamental design for a needle cartridge, as shown and described.

DESCRIPTION

FIG. 1 is a top, front, right perspective view of a needle cartridge, showing my new design;

FIG. 2 is a bottom, front, left perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top plan view thereof; and,

FIG. 8 is a bottom plan view thereof.

The broken lines of even length shown in the drawings illustrate portions of the needle cartridge that form no part of the claimed design.

1 Claim, 8 Drawing Sheets
